UNITED STATES PATENT OFFICE.

GEORGE W. NEELY, OF SANTA ANA, CALIFORNIA.

DRILL BIT.

Application filed August 9, 1923. Serial No. 656,572.

To all whom it may concern:

Be it known that I, GEORGE W. NEELY, a citizen of the United States, residing at Santa Ana, in the county of Orange and State of California, have invented certain new and useful Improvements in Drill Bits, of which the following is a specification.

This invention relates to bits for use in machinery for boring deep wells. With bits as heretofore constructed, loss of bits and great damage to the boring apparatus has been frequently caused by the bit striking a crevice in the rock and becoming jammed in the crevice so that it is twisted or broken from the drill tube or other supporting and driving elements, and it has been necessary frequently to abandon wells after they have been driven to great depth by reason of the inability to recover the broken bit and there-
10 by clear the well. Even when the broken bit has been recovered, considerable expense has been occasioned and time has been lost in the operation of fishing for the broken bit to remove the same from the well. It is
15 the object of my invention to provide a bit of such construction that, if a crevice in the rock should be encountered, the bit will not become jammed therein but will at once ride out of the crevice so that the entire boring
20 line will be raised and the operator at the mouth of the well will be notified of the condition. The boring tool may then be simply withdrawn and the usual means resorted to
25 for clearing away the obstructing portion
30 of the rock so that the drilling may proceed. One embodiment of my invention is illus-
35 trated in the accompanying drawing, and the invention resides in certain novel fea-
40 tures which will be particularly pointed out in the appended claims.

In the drawings:

Figure 1 is an elevation of a bit constructed in accordance with my invention and showing the same as engaged in a crevice in the rock and also showing by dotted lines the position of the bit after it rides out of the crevice;

Fig. 2 is a front elevation of the bit;

Fig. 3 is a bottom plan view, and

Fig. 4 is a detail section on the line 4—4 50 of Fig. 2.

The bit comprises a shank 1 which may be of any preferred form whereby it may be engaged in the drilling tube or other driving member in the usual manner. At the lower 55 end of the shank 1 is a head 2 having a sharpened lower cutting edge 3 and having the usual openings 4 formed therethrough for the flow of flushing water. The ends of the head are disposed obliquely relative to 60 the downwardly converging faces of the head and at one end of each face a guide lip 5 projects from the face in alinement with the end surface of the bit, as shown clearly in Fig. 3. The guide lips are dis- 65 posed at opposite ends of the bit so that each lip will run in advance of the face from which it projects when the tool is ro-
tated. The forward edge of each lip is
70 curved, as shown at 6, so that it presents a cam surface which, upon striking the edge of a crevice in the rock, as shown at 7, will cause the bit to ride upwardly out of the crevice, and this upward movement of the bit will be transmitted to and through the 75 entire driving line.

By referring to Fig. 1, it will be readily noted that the curved edge 6 of the bit con-
stitutes a cam which tends at once to ride upon the wall of the crevice and divert and 80 reverse the axial travel of the bit, whereas with the usual construction of bit, when a crevice is encountered, the cutting end of the bit will simply drop into the crevice and become wedged therein so that an attempt to 85 continue the rotation of the bit will simply break the shank of the same and jam the operating mechanism with resulting damage as hereinbefore mentioned.

My improved bit is exceedingly simple 90 in its construction and may be produced at a cost very little, if any, greater than the ordinary bits now generally employed. The saving of time and of machinery due to its use will more than off-set any additional 95 cost which may be involved in its manu-
facture.

It is to be understood that my improve-

ment may be applied to any form of bit employed in boring oil wells.

Having thus described the invention, what is claimed as new is:

- 5 1. A bit for deep wells comprising a cutting head provided at its opposite ends upon its opposite sides with forwardly projecting cam guide lips.

2. A rotary drill bit for deep wells comprising a cutting head provided at its ends 10 upon its opposite sides with forwardly projecting guide lips having their vertical edges curved to present cam faces.

In testimony whereof I affix my signature.

GEORGE W. NEELY. [L.S.]
